Primary Examiner — Alison M Ofstun*Assistant Examiner* — Evin Franklin George Ershock(74) Attorney, Agent, or Firm — Gloria Tsui-Yip; Gottlieb, Rackman & Reisman, P.C.(57) CLAIM

The ornamental design for a brush with removable cushion, as shown and described.

DESCRIPTION

FIG. 1 is a perspective view of a brush with removable cushion of my new design;

FIG. 2 is a left side elevational view thereof;

FIG. 3 is a top plan view thereof;

FIG. 4 is a right side elevational view thereof;

FIG. 5 is a bottom plan view thereof;

FIG. 6 is a rear elevational view thereof;

FIG. 7 is a front elevational view thereof;

FIG. 8 is another perspective view thereof; and,

FIG. 9 is an exploded, perspective view.

The broken lines in the drawings depict portions of the brush that form no part of the claimed design.
